UNITED STATES PATENT OFFICE

GEORGE HAZELTON AND THOMAS BAGGOTT CLARKE, OF LEICESTER, ENGLAND, ASSIGNEES TO UNITED SHOE MACHINERY CORPORATION, OF PATERSON, NEW JERSEY, A CORPORATION OF NEW JERSEY

APPARATUS FOR CONDITIONING PARTS OF SHOES

Application filed November 11, 1930, Serial No. 494,941, and in Great Britain January 3, 1930.

This invention relates to apparatus for conditioning parts of shoes and is herein disclosed as embodied in an apparatus adapted to condition unlayed breast-flaps of Louis-heeled shoes in accordance with a method described in a copending joint application of Gouldbourn and Hazelton, Serial No. 418,372, filed January 3, 1930.

According to the method referred to above, one or both of the complementary attaching faces of a breast-flap and the heel of a Louis-heeled shoe are coated with a soluble adhesive substance that is permitted to dry or set on the part or parts before the parts are assembled. Preferably, both of the complementary attaching faces are so coated, although it is within the scope of the invention set forth in that application to coat only one of them, but in either case the method referred to consists, in part, in reviving the tacky condition of the adhesive substance, by a suitable solvent, at that stage in the manufacture of a shoe when the attached heel is ready to have the breast-flap secured thereto. The method also provides for tempering the grain surface of the breast-flap with hot moist vapor whereby the flap will be rendered so pliable that it may be readily conformed to the curvatures of the breast-face of the heel and will be thereby deprived, to a great extent, of whatever tendency it might otherwise have to spring away from the breast of the heel after removal of the pressure by which it is so conformed.

An object of the present invention is to provide improved apparatus with which to temper a breast-flap and to revive the tacky condition of a dried adhesive that may have been used to coat the breast-flap or the breast-face of the heel or both, as explained above, to the end that the practice of the method referred to may be facilitated.

To this end, a feature of the present invention consists in an apparatus comprising means constructed and arranged to support a

Louis-heeled shoe so that an unlayed breast-flap thereof may hang without being supported otherwise than by the shoe, and means arranged to supply a conditioning fluid to the attaching face of the breast-flap and to the breast of the heel.

To avoid the necessity of supplying two different kinds of treating fluid, one to revive the tacky condition of the adhesive substance and the other to temper the grain surface of the breast-flap, it is desirable to use an adhesive substance, such as glue, that will be revived by hot moist vapor, since such vapor is more satisfactory than any other treating medium with which to temper the grain surface of a breast-flap. Accordingly, the apparatus illustrated herein provides for supplying hot moist vapor to the grain surface of a breast-flap and to the complementary attaching faces of the breast-flap and the heel. Preferably, and as herein illustrated, the vapor for these two purposes is emitted from individual nozzles simultaneously, the nozzles being arranged to cause the jets to converge upwardly under the shank portion of a shoe supported in position for treatment. It is to be understood, however, that the invention is not limited to the use of the same conditioning medium for both purposes since it would be entirely consistent with the principles of the invention to supply one kind of conditioning fluid for tempering the grain surface of the breast-flap and another kind of fluid for reviving the tacky condition of the adhesive substance.

Referring to the accompanying drawing,

Fig. 1 is a side elevation, partly in section, of a conditioning apparatus embodying the present invention, the view omitting a detachable plate that forms one of the upright walls of the chamber in which the conditioning fluid is emitted;

Fig. 2 is a top plan view of the apparatus shown in Fig. 1 with the addition of the detachable plate omitted from Fig. 1; and

Fig. 3 is an elevation of the interior surface of the upper portion of the detachable plate.

A hollow aluminum structure comprising a member 10 and a detachable front wall or plate 12 is held assembled by clamping screws 14 and is provided with anchoring members 16 and 18 (Fig. 2) by which it may be fastened to a convenient support. The members 10 and 12, when assembled, form a chamber 20 which is open only at the top. The opening at the top of the chamber is too small to receive a shoe but it will receive the tip of an unlaid breast-flap 22 hanging from the shank 24 of a Louis-heeled shoe placed as shown in Fig. 1. The detachable wall 12 confronts a rear wall 26, these two walls being spaced apart a distance slightly greater than the width of the waist portion of a Louis-heeled shoe, their upper margins 10 projecting above the two upright connecting walls 28 and 30 to provide a channel for the reception of the shank portion and the heel of a shoe. The upper edge of the wall 26 is indicated by the line 32 in Fig. 1, while the corresponding upper edge of the wall 12 is 15 preferably provided with a strip 34 of soft flexible material, such as rubber. Viewed in elevation, the edge 32 and the strip 34 conform approximately to the longitudinal curvature of the arch of a Louis-heeled shoe (see Fig. 1). Moreover, the inner edge 36 of the strip 34 (see Fig. 2) is preferably shaped to conform in general to the plan 20 configuration of the shank portion of a shoe so that it will lie in contiguous relation to the body of the shoe just above the crease between the upper and the sole. Thus, the upper portions of the walls 12 and 26 will 25 be so close to the waist or shank portion of a shoe as to cooperate with the shoe to restrict the escape of vapor from the opening at the top of the chamber 20.

As shown in Fig. 1, the upper edge of the 20 wall 28 and the upper edge of the opposite wall 30 are arranged to provide platforms substantially at a common level for the ball portion and the heel, respectively, of a shoe, the heel-supporting platform including a flat 25 horizontal flange 38. A horizontally adjustable abutment is arranged over the flange 38 to engage the back of a heel. This abutment comprises a metallic block 40 and an insert 42 of relatively soft material, such as felt, 30 the block 40 being provided with a groove in which the element 42 is maintained frictionally or by an adhesive. A screw-threaded stem 44 projects from the block 40 through a horizontal slot 46 in the upwardly projecting portion of the wall 26 and is provided with a thumb-nut 48 by which the abutment 35 may be clamped at any desired position. Preferably, this abutment will be adjusted to locate the breast-face of a heel in flush relation to the inner face of the wall 30.

A pipe 50 for supplying steam or hot moist vapor extends through the rear wall 26 of the hollow structure 10 and is preferably provided with two branches or emission nozzles 52 and 54, the portion connecting the nozzles being inclined and having a downwardly projecting nozzle 56 for draining the water of condensation so that vapor only will be sprayed on the work. The nozzle 56 projects into a cup or cavity 58 formed in the bottom 70 wall 60 of the hollow structure 10. When this cup is filled with water of condensation it seals the nozzle 56 against the escape of steam or vapor at that point. As the water of condensation overflows the cup 58, it flows into a drain-pipe 62, the bottom wall 60 being inclined to cause the overflow to gravitate toward the drain-pipe.

Any suitable or preferred means may be provided to supply steam or hot moist vapor 85 through the pipe 50 but we prefer an apparatus that will generate such vapor at a pressure only slightly greater than that of the atmosphere because it is not desirable to subject the work to excessive heat or to wet it 90 more than enough to temper the breast-flap 22 and to revive the tacky condition of the adhesive substance.

The nozzles 52 and 54 are arranged to emit 95 upwardly converging jets of steam or vapor, the jet emitted by the nozzle 52 being directed toward the grain surface of the breast-flap and the jet emitted by the nozzle 54 being directed to play between the breast-flap and the breast-face of the heel.

To insure sufficient space in which this jet may do its work, the apparatus is provided with a horizontal pin 64 arranged to maintain the breast-flap away from the heel as shown in Fig. 1. This pin is preferably mounted 100 so that it may be adjusted both horizontally and vertically according to the requirements of the articles of work presented for treatment. Accordingly, the pin is fastened to a plate 66 from which a screw-threaded stem 68 projects through a vertical slot 70 formed in the rear wall 26. The stem 68 is provided with a thumb-nut 72 by which the plate 66 may be clamped against the wall 26, the slot 70 providing for vertical adjustment of the 105 pin 64 while horizontal adjustment of the pin may be effected by turning the device about the axis of the stem 68.

When a shoe stands on the apparatus as shown in Fig. 1, the breast-flap 22 and the heel are masked by the upwardly projecting margins of the walls 12 and 26, the steam or vapor from the chamber 20 being thereby maintained for a considerable time in the vicinity of the elements to be treated thereby. It is desirable, however, that the user may observe whether the pin 64 functions as intended, to maintain the breast-flap away from the heel. For this reason, the detachable wall 12 is preferably provided with an insert 74 110

of transparent material such as glass, the location of which is in register with the breast-flap and the pin 64. When a breast-flap is correctly engaged with the pin 64, it is maintained between the lines of convergence of the jets issuing from the nozzles 52 and 54, the two jets being thereby caused to impinge, respectively, against the opposite faces of the breast-flap.

10 The escape of steam or vapor from the chamber 20 is so greatly retarded by the overlying shank portion of the shoe that it accumulates in the vicinity of the breast-flap 22 and is evenly distributed over the surfaces 15 that require treatment, the breast-flap, more than any other part of the shoe, being subjected to the influence of the vapor not only because of its position between the converging jets of vapor but also because it hangs in the 20 opening at the top of the chamber 20. The relative positions of the nozzles 52 and 54 may be varied according to the characteristics of the work in the particular factory in which the apparatus is used. Moreover, these nozzles 25 are preferably made of copper piping or other ductile metal capable of being easily bent as may be required to regulate the disposition of the jets emitted from them.

Having thus described our invention, what 30 we claim as new and desire to secure by Letters Patent of the United States is:

1. A conditioning apparatus comprising means constructed and arranged to support a Louis-heeled shoe, means arranged to maintain an unlayed breast-flap thereof away from the heel, and means arranged to spray a conditioning fluid on the breast of the heel.

2. A conditioning apparatus comprising means constructed and arranged to support a Louis-heeled shoe, means arranged to maintain an unlayed breast-flap thereof away from the heel, and means arranged to spray a conditioning fluid on the attaching face of the breast-flap.

45 3. A conditioning apparatus comprising means constructed and arranged to support a Louis-heeled shoe, means arranged to maintain an unlayed breast-flap thereof away from the heel, and means arranged to spray a conditioning fluid on both faces of the breast-flap simultaneously.

4. A conditioning apparatus comprising means constructed and arranged to support a Louis-heeled shoe, means arranged to maintain an unlayed breast-flap thereof away from the heel, and means by which individual jets of conditioning fluid are sprayed simultaneously on the breast of the heel and on one face of the breast-flap.

60 5. A conditioning apparatus comprising means constructed and arranged to support a Louis-heeled shoe, means arranged to maintain an unlayed breast-flap thereof away from the heel, and means by which individual jets of conditioning fluid are sprayed simul-

taneously on opposite faces of the breast-flap.

6. A conditioning apparatus comprising means constructed and arranged to support a Louis-heeled shoe so that an unlayed breast-flap thereof may hang without being supported otherwise than by the shoe, and means arranged to supply a conditioning fluid to the attaching face of the breast flap.

7. A conditioning apparatus comprising means constructed and arranged to support a Louis-heeled shoe so that an unlayed breast-flap thereof may hang without being supported otherwise than by the shoe, and means arranged to supply a conditioning fluid to the breast of the heel.

8. A conditioning apparatus comprising means constructed and arranged to support a Louis-heeled shoe so that an unlayed breast-flap thereof may hang without being supported otherwise than by the shoe, and means arranged to supply a conditioning fluid to the attaching face of the breast-flap and to the breast of the heel.

9. A conditioning apparatus comprising means constructed and arranged to support a Louis-heeled shoe so that an unlayed breast-flap thereof may hang without being supported otherwise than by the shoe, means arranged to maintain the breast-flap away from the heel, and means arranged to supply a conditioning fluid to the attaching face of the breast-flap.

10. A conditioning apparatus comprising means forming a chamber having an opening at the top, two portions of said means at opposite sides of said opening having work-supporting surfaces at the level of said opening so arranged that the ball portion and the heel of a Louis-heeled shoe may stand on them while an unlayed breast-flap hanging from the shoe projects through said opening and into said chamber, and means by which hot moist vapor is supplied to said chamber.

11. A conditioning apparatus comprising means forming a chamber open at the top to receive a portion of an unlayed breast-flap hanging from a Louis-heeled shoe, means arranged to support a shoe over said chamber, means by which hot moist vapor is supplied to said chamber, and means arranged to maintain the breast-flap away from the heel.

12. A conditioning apparatus comprising means forming a chamber having an opening at the top, two portions of said means at opposite sides of said opening having work-supporting surfaces at the level of said opening so arranged that the ball portion and the heel of a Louis-heeled shoe may stand on them while a portion of an unlayed breast-flap hanging from the shoe projects through said opening and into said chamber, means by which hot moist vapor is supplied to said chamber, and confronting members spaced apart and arranged to cooperate with the shank portion of a shoe standing on said

surfaces to restrict the escape of vapor from the vicinity of the breast-flap.

13. A conditioning apparatus comprising a walled vapor-confining chamber open at the top to receive a portion of an unlayed breast-flap hanging from a Louis-heeled shoe, two opposite walls forming the opening at the top of said chamber being platforms respectively for the heel and the ball portion of a shoe, and means by which hot moist vapor is supplied to said chamber.

14. A conditioning apparatus comprising means forming a chamber having an opening at the top, two opposite walls forming said opening being arranged to function as platforms respectively for supporting the heel and the ball portion of a shoe having an attached heel, means by which hot moist vapor is supplied to said chamber, and two confronting elements spaced apart and arranged above the levels of said shoe-supporting platforms to extend along and adjacent to the opposite sides of the shank portion of the shoe whereby a shoe standing on said platforms is rendered effective to restrict the escape of vapor from said chamber.

15. A conditioning apparatus comprising means forming a chamber open at the top to receive a portion of an unlayed breast-flap hanging from a Louis-heeled shoe, two opposite walls forming the opening at the top of said chamber being arranged to provide platforms respectively for the heel and the ball portion of a shoe, means by which hot moist vapor is supplied to said chamber, and horizontally adjustable means arranged to be engaged by the back of a heel to locate the breast of the heel adjacent to the rim of the opening at the top of said chamber.

16. A conditioning apparatus comprising two supporting elements spaced apart and arranged to support a Louis-heeled shoe by engaging respectively the heel and the ball portion thereof, means by which two upwardly converging jets of treating fluid are emitted under the shank portion of a shoe so supported, and means arranged to maintain an unlayed breast-flap of the shoe between the lines of convergence of said jets.

17. A conditioning apparatus comprising means arranged to support a Louis-heeled shoe in a certain position for treatment, means arranged to maintain an unlayed breast-flap thereof away from the breast of the heel, means by which hot moist vapor is supplied to the grain surface of the breast-flap, and means by which an individual supply of treating fluid is applied to the complementary attaching faces of the breast-flap and the heel.

18. A conditioning apparatus comprising a hollow structure open at the top and having two upwardly projecting and confronting walls formed and arranged to mask the shank portion of a Louis-heeled shoe stand-

ing between them, means by which an unlayed breast-flap hanging from the shoe is maintained away from the heel, the portion of one of said walls that controls a view of said means being composed of transparent material, and means by which a treating fluid is applied to the breast-flap.

In testimony whereof we have signed our names to this specification.
